CLAIM

The ornamental design for a mount for television, display device or the like, as shown and described.

DESCRIPTION

FIG. 1 is a front and left side perspective view of a mount for television, display device or the like showing my design; FIG. 2 is a rear and right side perspective view thereof; FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines seen in the drawing depict portions of the mount for television, display device or the like that form no part of the claimed design.

1 Claim, 8 Drawing Sheets
